Primary Examiner — Stacia Cadmus(74) *Attorney, Agent, or Firm* — QuickPatents, LLC;
Kevin Prince(57) **CLAIM**

I claim the ornamental design for a hub cap, as shown and described.

DESCRIPTION

FIG. 1 is a perspective view of a hub cap, showing my new design;

FIG. 2 is an exploded perspective view thereof;

FIG. 3 is a front elevational view thereof;

FIG. 4 is a left-side elevational view thereof; the right-side elevational view being a mirror image thereof;

FIG. 5 is a rear elevational view thereof; and,

FIG. 6 is a top plan view thereof, the bottom plan view being a mirror image thereof.

The broken lines showing a wheel and a fanciful number 23 indicia in FIG. 1 and a wheel in FIG. 2 depict environmental matter and form no part of the claimed design. The hub cap is shown on an enlarged scale in FIGS. 3-6.
